RADIO TRANSMITTING SYSTEM

Application filed May 23, 1925. Serial No. 32,360.

My invention relates to the simultaneous transmission of a plurality of telegraphic or telephonic signals or messages represented by electro-radiant energies in radio systems, or by carrier wave currents in conductor systems, utilizing different frequencies derived from a single oscillatory source, one or more of the frequencies being harmonics of the fundamental oscillations produced by the oscillator and one of the signals or messages being represented by electro-radiant energy of the fundamental frequency of the oscillations produced by the oscillator.

In accordance with my invention, electro-radiant energy of the frequencies of the fundamental frequency of oscillations may be utilized, and one or more harmonics of the fundamental frequency is or are reinforced and amplified and utilized for transmission of one or more separate and distinct signals or messages.

Further in accordance with my invention, there are coupled with the inductance of an oscillatory circuit traversed by oscillations of fundamental frequency one or more circuits tuned to the desired harmonic or harmonics, and with each tuned circuit is associated suitable amplifying apparatus, as a thermionic amplifier or a plurality of them in staged relation, with means for impressing the amplified harmonic upon a radiating or carrier wave conducting system; and further in accordance with my invention, a system for radiating or conducting the energy at the fundamental frequency may also be coupled to the circuit traversed by oscillations of fundamental frequency.

My invention resides in a method and system of the character hereinafter described.

For an understanding of my method and for an illustration of various forms my apparatus may take, reference is to be had to the accompanying drawing, in which:

Fig. 1 is a diagrammatic view of a system for transmitting both fundamental and harmonic frequencies derived from oscillations produced by an arc.

Fig. 2 is a fragmentary diagram of a modification wherein a thermionic oscilla-

tor is utilized in lieu of the arc of Fig. 1.

Referring to Fig. 1, G represents a suitable source of current, as, for example, a dynamo-electric generator supplying direct current through the high frequency choke coils f , f to the electrodes P and N of an arc in shunt to which are connected the inductance or common primary L and the condenser C. In the circuit L, C will be produced free oscillations of fundamental frequency dependent practically upon the product of the inductance L by the capacity of the condenser C. Coupled to the common primary or inductance L is the secondary S^1 , connected through condenser C^1 to earth or counter-capacity E and to the key K, which when depressed engages the contact k to bring into communication with the secondary S^1 the radiating antenna A^1 provided, if suitable or desirable, with the loading inductance L^1 . With the key in the position mentioned, there will be radiated sustained high frequency energy of the fundamental frequency produced by the arc. When the key is raised into engagement with the upper contact k^1 , there is brought into circuit with the secondary S^1 the inductance L^2 , condenser C^2 and resistance R, representing a combination of resistance, capacity and inductance corresponding to that of the antenna A^1 and its inductance L^1 , the key being at a position of potential node in the system.

Coupled to the common primary or inductance L is the secondary S^2 , shunted by the tuning condenser C^3 for tuning the circuit to a suitable harmonic of the fundamental frequency. Assuming the fundamental wave length to be 2,400 meters, the circuit S^2 , C^3 may be attuned, for example, to the sixth harmonic, or to a wave length of 400 meters. This harmonic is amplified by the thermionic amplifier V, whose anode circuit is coupled to the antenna A^2 , which radiates energy of the sixth harmonic frequency, the antenna A^2 being attuned to that frequency. The tuned circuit S^2 , C^3 serves to reinforce the selected harmonic, and encourage its development in the circuit L, C.

Similarly, the antennas A^3 and A^4 , tuned, respectively, to other harmonics, as, for example, the tenth and thirtieth harmonics, respectively, are supplied by reinforced and amplified harmonics whose energy is derived from the circuit L , C and in which circuit these harmonics are reinforced by the tuned grid circuits of the thermionic amplifiers V^1 and V^2 comprising with the tube V^1 the secondary S^3 and tuning condenser C^4 , and for the tube V^2 the secondary S^4 shunted by the tuning condenser C^5 .

In the grid lead of each of the tubes V , V^1 and V^2 may be connected suitable key mechanisms K^1 , K^2 and K^3 , respectively, for controlling the radiated energy in accordance with telegraphic signals.

Obviously, however, in lieu of one or more or all of the telegraphic keys K^1 , K^2 , K^3 there may be used microphone transmitters 20 controlling the potentials of the grids of the respective tubes in well known manner, whereby with different harmonics, reinforced and amplified, several different telephonic 25 messages may be simultaneously transmitted, and simultaneously the fundamental may be utilized for transmitting through the instrumentality of the antenna A^1 .

To prevent energy in any of the antennas 30 A^2 , A^3 or A^4 reacting upon the anode circuit of the associated amplifier tube, and there-through upon the grid circuit and/or through the grid circuit upon the circuit L , C , the anode circuit is not connected directly to the cathode of the tube, but at a suitable point in the secondary S^2 , S^3 or S^4 , thereby rendering the anode circuit electrically symmetrical with respect to the input or grid circuit, preventing the reverse 40 energy flow described, and preventing production of individual oscillations by each of the vacuum tubes.

While in Fig. 1 an arc oscillator is shown, it will be understood that any other type of 45 oscillator may be utilized, as, for example, a thermionic oscillator, as indicated in Fig. 2, which illustrates an oscillator of well known type producing free oscillations by means of the thermionic tube V^3 , in whose anode circuit is a portion of the inductance L and in whose grid circuit is the remainder thereof, with the condenser C connected across the terminals of the entire inductance L . Coupled to the common primary or inductance L 50 are the aforesaid secondaries S^1 — S^4 , related, as described in connection with Fig. 1, with the several antennæ A^1 — A^4 .

In the case of both Fig. 1 and Fig. 2, it 60 will be found desirable properly to locate the secondaries S^2 , S^3 and S^4 with respect to each other along the common primary or inductance L . In general, each secondary should be located at such region along the inductance L that there occurs thereat a cur-

rent anti-node as regards the harmonic to be taken off by that secondary.

The common primary or inductance L is preferably a continuous coil or winding, as indicated, for under such circumstances its distributed capacity is greater than in case it were divided into sections, one for each secondary S^1 — S^4 , and with greater distributed capacity the production, reinforcement and amplification of harmonics is facilitated. It 70 will be understood, however, that as regards the broader aspects of my invention the inductance L may be comprised of separate serially connected primaries inductively related, respectively, to the secondaries S^1 , S^4 . 75 80

While I have more particularly referred to the impression of energies of different frequencies upon antennæ or radiating structures, for radio systems, it will be understood that in lieu of such antennæ there may be utilized conductors extending between transmitting and receiving stations, as in carrier wave telephony, telegraphy and the like.

What I claim is:

1. The method which comprises producing current of fundamental radio frequency, effecting flow of the unamplified current in a current path, reactively coupling to said path a circuit resonant to a harmonic of said fundamental frequency to encourage development of oscillations of said harmonic frequency in said path, controlling the current of fundamental frequency to represent a signal or message, controlling the oscillations of harmonic frequency to represent a different signal or message, and impressing upon the natural media disassociated electro-radiant energies having, respectively, said fundamental and harmonic frequencies. 95 100 105

2. The method which comprises correlating an arc with capacity and inductance to effect production of oscillations of fundamental and harmonic frequencies selecting therefrom oscillations of harmonic frequency, individually controlling the oscillations of fundamental and harmonic frequencies to represent different signals or messages, amplifying the energy of harmonic frequency, impressing upon the natural media electro-radiant energy of the amplified harmonic frequency, and impressing upon the natural media electro-radiant energy of said fundamental frequency without amplification thereof. 110 115 120

3. The method which comprises correlating an arc with capacity and inductance to effect production of oscillations of fundamental frequency, deriving therefrom oscillations of harmonic frequency, transmitting a signal or message represented by the oscillations of harmonic frequency, transmitting a different signal or message represented by oscillations of fundamental frequency, and maintaining conjugate the transmission paths for the oscillations of har- 125 130

monic frequency with respect to reverse energy flow to a path traversed by oscillations of said fundamental frequency.

4. The method which comprises correlating an arc with capacity and inductance to effect production of oscillations of fundamental frequency, deriving therefrom oscillations of harmonic frequency, amplifying said oscillations of harmonic frequency, transmitting a signal or message represented by the oscillations of harmonic frequency, transmitting a signal or message represented by oscillations of fundamental frequency without amplification thereof, and maintaining conjugate the transmission paths for the oscillations of harmonic frequency with respect to reverse energy flow to a path traversed by oscillations of said fundamental frequency.

5. Transmitting apparatus comprising an arc, capacity and inductance related to produce oscillations of fundamental frequency, means for abstracting oscillations of harmonic frequency from said inductance at a region therein anti-nodal with respect to current of said harmonic frequency, means for transmitting a signal or message represented by the oscillations of harmonic frequency, means for abstracting from said inductance at a different region thereof oscillations of another frequency, said different region being anti-nodal with respect to current of said other frequency, and means for transmitting signals or messages represented by the oscillations of said other frequency.

6. Transmitting apparatus comprising means associated with capacity and inductance to produce free oscillations of fundamental frequency, means resonant to a harmonic frequency for reinforcing in said inductance oscillations of said harmonic frequency, means for transmitting a signal or message represented by the oscillations of harmonic frequency, and means for preventing reverse energy flow from a transmitting path to said inductance.

7. Transmitting apparatus comprising means associated with capacity and inductance to produce free oscillations of fundamental frequency, means resonant to a harmonic frequency for reinforcing in said inductance oscillations of said harmonic frequency, said inductance having characteristics causing accentuation therein of oscillations of harmonic frequency, means for amplifying the oscillations of harmonic frequency, and means for transmitting a signal or message represented by the oscillations of harmonic frequency.

8. Transmitting apparatus comprising an arc, inductance and capacity related to produce oscillations of fundamental frequency, said inductance having characteristics causing accentuation therein of oscillations of harmonic frequency, means for transmitting

a signal or message represented by the oscillations of harmonic frequency, means for abstracting from said inductance oscillations of fundamental frequency, and means for transmitting signals or messages represented by said oscillations of fundamental frequency.

9. Transmitting apparatus comprising an arc, inductance and capacity related to produce oscillations of fundamental frequency, means resonant to a harmonic frequency for reinforcing in said inductance oscillations of said harmonic frequency, means for transmitting a signal or message represented by the oscillations of harmonic frequency, means for abstracting from said inductance oscillations of fundamental frequency, means for transmitting signals or messages represented by said oscillations of fundamental frequency, and means for preventing reverse energy flow from a transmitting path to said inductance.

10. Transmitting apparatus comprising an arc, inductance and capacity related to produce oscillations of fundamental frequency, said inductance having characteristics causing accentuation therein of oscillations of harmonic frequency, means resonant to a harmonic frequency for reinforcing in said inductance oscillations of said harmonic frequency, means for amplifying the oscillations of harmonic frequency, means for transmitting a signal or message represented by the oscillations of harmonic frequency, means for abstracting from said inductance oscillations of fundamental frequency, and means for transmitting signals or messages represented by said oscillations of fundamental frequency at substantially their original amplitude.

11. Transmitting apparatus comprising means for producing current of fundamental radio frequency in a circuit, a tuned circuit coupled to said first circuit to promote therein and derive therefrom oscillations of harmonic frequency, means individually controlling the oscillations of fundamental and harmonic frequencies to represent different signals or messages, and means for impressing upon the natural media disassociated electro-radiant energies having, respectively, said fundamental and harmonic frequencies comprising independent antenna structures.

12. Transmitting apparatus comprising an arc, capacity and inductance associated therewith to effect production of oscillations of fundamental and harmonic frequencies, means selecting therefrom oscillations of harmonic frequency, means individually controlling the oscillations of fundamental and harmonic frequencies to represent different signals or messages, and means for impressing upon the natural media electro-radiant energies having, respectively, said fundamental and harmonic frequencies.

13. Transmitting apparatus comprising an arc, capacity and inductance associated therewith to effect production of oscillations of fundamental and harmonic frequencies, means directly selecting therefrom oscillations of harmonic frequency, means individually controlling the oscillations of fundamental and harmonic frequencies to represent different signals or messages, means for amplifying the energy of harmonic frequency, means for impressing upon the natural media electro-radiant energy of the amplified harmonic frequency, and means for impressing upon the natural media electro-radiant energy of said fundamental frequency at substantially its original amplitude. 130
14. Transmitting apparatus comprising inductance and capacity correlated to effect production of free oscillations of fundamental and harmonic frequencies, transmitting circuits resonant to the fundamental and harmonic frequencies, means for magnetically coupling the transmitting circuits to the inductance to permit transfer of oscillations of selected frequency from the inductance through the transmitting circuits, and means preventing the production of sustained free oscillations in the transmitting circuits. 20
15. Transmitting apparatus comprising means associated with capacity and inductance to produce free oscillations of fundamental frequency, a resonant circuit for abstracting oscillations of harmonic frequency from said inductance, a signaling circuit for utilizing said harmonic frequency oscillations, and a symmetrical connection between said signaling circuit and the resonant circuit arranged to prevent the feedback of harmonic frequency to said inductance. 35
16. Transmitting apparatus comprising means associated with capacity and inductance to produce free oscillations of fundamental frequency, amplifying means resonant to a harmonic frequency comprising an input circuit magnetically coupled to said inductance and an output circuit normally in energy transfer relation to said input circuit, and means for controlling the extent of such energy transfer in order to prevent the production of individual oscillations in said amplifying means. 50
17. Transmitting apparatus comprising means associated with capacity and inductance to produce free oscillations of fundamental frequency, a circuit resonant to a harmonic frequency magnetically coupled to said inductance, an amplifier comprising an input circuit connected across the resonant circuit, and an output circuit symmetrically connected to the input circuit, whereby reverse energy flow and the production of individual oscillations in said amplifier are prevented. 65
18. Transmitting apparatus comprising a circuit including inductance and capacity correlated to effect production of oscillations of fundamental and harmonic frequencies, a transmitting circuit magnetically coupled to said first named circuit and abstracting therefrom oscillations of harmonic frequency, a transmitting medium, a thermionic amplifier of the three electrode type intervening between said transmitting circuit and transmitting medium, and a symmetrical connection between the output and input circuits of said amplifier. 70
19. Transmitting apparatus comprising a circuit including inductance and capacity correlated to effect production of oscillations of fundamental and harmonic frequencies, a transmitting circuit magnetically coupled to said first named circuit and abstracting therefrom oscillations of harmonic frequency, a transmitting medium, a thermionic amplifier of the three electrode type intervening between said transmitting circuit and transmitting medium, a symmetrical connection between the output and input circuits of said amplifier, and means for rendering the input circuit of said amplifier resonant to said harmonic frequency. 80
20. Transmitting apparatus comprising a circuit including an arc and correlated inductance and capacity for the production of oscillations of fundamental and harmonic frequencies, a structure for radiating energy of the fundamental frequency at substantially its original amplitude, means for controlling the energy of fundamental frequency to represent a signal or message, a second structure radiating energy of harmonic frequency, a thermionic amplifier of the three electrode type having input and output circuits and intervening between said first named circuit and said second radiating structure, a magnetic coupling between the input circuit of said amplifier and said first named circuit, and means intervening between said coupling and said thermionic amplifier rendering the circuit resonant to said harmonic frequency. 100
21. Transmitting apparatus comprising an arc, capacity and inductance associated therewith to effect production of oscillations of fundamental and harmonic frequencies, means directly selecting therefrom oscillations of harmonic frequency, means individually controlling the oscillations of fundamental and harmonic frequencies to represent different signals or messages, and means comprising independent antenna structures for impressing upon the natural media dissociated electro-radiant energies having, respectively, said fundamental and harmonic frequencies. 110
22. The method which comprises correlat- 130

ing an arc with capacity and inductance to effect production of oscillations of fundamental and harmonic frequencies, selecting therefrom oscillations of harmonic frequency, individually controlling the oscillations of fundamental and harmonic frequencies in separate paths to represent different signals or messages, and effecting transfer to the natural media from said separate paths of electro-radiant energies of, respectively, said fundamental and harmonic frequencies.

In testimony whereof I have hereunto affixed my signature this 19th day of May, 1925.
